UNITED STATES PATENT OFFICE.

JOHN FRITZ, OF NEW BEDFORD, MASSACHUSETTS.

PAPER-CLIP.

1,275,012.

Specification of Letters Patent. Patented Aug. 6, 1918.

Application filed December 20, 1916. Serial No. 137,992.

To all whom it may concern:

Be it known that I, JOHN FRITZ, a citizen of the United States, and a resident of New Bedford, in the county of Bristol and 5 State of Massachusetts, have invented certain new and useful Improvements in Paper-Clips, of which the following is a specification.

My invention relates to paper clips of 10 unit form, one of the main objects thereof being to provide a relatively large and strong prong which, after being forced through the paper to be bound together, is deflected and permanently seated in a 15 pocket, and another object is to provide relatively small supplemental prongs adapted, after having passed through the paper, to be seated in indentations to prevent lateral movement of the plate members of the 20 clip with respect to the paper and to each other.

My invention is fully described in the following specification, of which the accompanying drawings form a part, in which 25 like characters refer to like parts in each of the views, and in which:—

Figure 1 is a view of one side of my clip applied to one or more sheets of paper;

Fig. 2 is a similar view of the opposite 30 side thereof;

Fig. 3 is an enlarged central longitudinal section taken through my clip and through a sheet of paper, previous to clamping the clip in locking position;

Fig. 4 is a similar section, with the clip 35 clamped in locking position;

Fig. 5 is an enlarged section taken on the line 5—5 of Fig. 2;

Fig. 6 is a view of the clip, as marketed, 40 viewed toward its open end, with a sheet of paper in position; and

Fig. 7 is a section taken on the line 7—7 of Fig. 6.

Referring to the drawings, 8 represents 45 a puncturable sheet, or sheets, to which it is desired to secure my clip, the latter being formed of a strip 9 of thin sheet metal bent centrally on a transverse line to form two plate members 10 and 11, the former of 50 which has a relatively large prong 12 and two relatively small prongs 13 stamped

therefrom and bent toward the plate member 11, the lower end of the prong 12 being shown as slightly arcuate to offset the point thereof from the main portion thereof.

The lower plate member 11 has a pocket 55 14 stamped therein with an inclined bottom adapted to bend the point of the prong 12 and thus the prong itself to rest within said pocket, said plate member also having a 60 tongue 15 stamped therefrom and bent to partially cover said pocket and thus prevent the escape of the bent prong 12 from the pocket when the clip is clamped in place, Fig. 4, the end of said tongue being bent 65 downwardly into said pocket to prevent its interference with any sheets of paper introduced between the two plate members 10 and 11.

The plate member 11 is also provided with 70 two slight depressions 16 adapted to receive the small prongs 13, Fig. 5, when the clip is clamped into locking position to prevent lateral movement between the plate members and, thus between the clip and the 75 sheets bound thereby, the prongs 13 being slightly upset at their points when the clip is clamped, Fig. 5 showing only a partially clamped position.

Because of the large prong 12 my clip 80 is locked in place in a positive manner rendering the separation of the plate members 10 and 11 practically impossible, and because of the supplemental prongs 13 the clip is held motionless with respect to the 85 sheets of paper bound thereby.

The clip is very simple in construction and in use, as well as very inexpensive, and, while I have shown a preferred embodiment I reserve the right to make such changes 90 as come within the scope of the appended claim.

Having fully described my invention, what I claim as new, and desire to secure by Letters Patent, is:—

As a new article of manufacture, a paper 95 clip formed of a strip of sheet metal bent upon itself to form two members, one member being provided with a long and two short prongs struck up therefrom, the long 100 prong being at the center and the short prongs adjacent the sides of the member,

the other member, opposite the long prong, being bent downwardly to form a recess having an inclined bottom, and provided with side openings to receive the short
5 prongs and with a tongue struck up therefrom between the recess and the junction of the two members, the said tongue being bent

downwardly and extending partially over the recess and forming therewith a pocket to receive the said long prong.

JOHN FRITZ
